UNITED STATES PATENT OFFICE.

F. ROBERT SEIDENSTICKER, OF WEST MERIDEN, CONN., ASSIGNOR TO
BRADLEY & HUBBARD MANUFACTURING COMPANY, OF SAME PLACE.

DESIGN FOR LAMP-BRACKETS.

Specification forming part of Design No. **11,466**, dated October 21, 1879; application filed September 19, 1879.
[Term of patent 7 years.]

To all whom it may concern:

Be it known that I, F. ROBERT SEIDENSTICKER, of West Meriden, in the county of New Haven and State of Connecticut, have invented a new Design for Lamp-Brackets; and I do hereby declare the following, when taken in connection with the accompanying drawing and the letters of reference marked thereon, to be a full, clear, and exact description of the same, and which said drawing constitutes part of this specification, and represents a side view.

This invention relates to a design for lamp-bracket arm; and it consists in the configuration, as hereinafter described, and shown in the accompanying illustration.

From the post *a* two branches extend outward, one turning upward and the other downward, both in scroll-work form. To the lower branch the main arm of the bracket is attached. This arm is of **U** shape, gradually expanding from the post, where it is attached, downward to the center, thence continuing upward and terminating in the basket-rest *b*. At the center is a representation of the key and cock, and with scroll branch-work extending from the edge of the arm out beneath the fount-rest as if for a brace, all as shown in the accompanying illustration.

The basket starts from the rest, expanding in a curved shape to a reeded oval, *c*, above which is a plain cavetto, and from which the

sides rise, gradually expanding, crowned by a projecting scallop and point molding. In the sides of the basket are arched openings with a leaf-work between, all as shown in the accompanying illustration.

The arm is applicable to a wall-bracket or to a chandelier.

The basket may be used upon brackets of other designs, or other designs of baskets may be used with this bracket. This application is therefore not to be understood as combining this particular basket with this particular bracket.

I claim—

1. The design for lamp-bracket arm, consisting of the two scroll-work branches springing from the post *a*, with the principal arm represented as supported by and extending from the lower branch, gradually expanding and curved downward to the center, then curved upward to the fount-rest *b*, and with the representation of the key at the center, all as shown in the accompanying illustration.

2. The design for fount-basket for lamp-brackets, consisting of the molded bottom, flaring sides with arch-openings, crowned by scallops, and point-edge, as shown in the accompanying illustration.

F. ROBT. SEIDENSTICKER.
